Patented June 22, 1920.

FIG. 1.

FIG. 2.

FIG. 3.

Inventor

Joseph Mersman

By

Edward E. Clements
Notary

UNITED STATES PATENT OFFICE.

JOSEPH MERSMAN, OF OTTAWA, OHIO.

SOUND-AMPLIFIER.

1,344,307.

Specification of Letters Patent. Patented June 22, 1920.

Application filed May 12, 1919. Serial No. 296,517.

To all whom it may concern:

Be it known that I, JOSEPH MERSMAN, a citizen of the United States, residing at Ottawa, in the county of Putnam and State of Ohio, have invented certain new and useful Improvements in Sound-Amplifiers, of which the following is a specification, reference being had therein to the accompanying drawing.

10 My invention relates to sound reproducing machines and more particularly to a horn or amplifier therefor.

An object of my invention is to provide a horn or amplifier which will amplify the 15 sound reproduced by the sound box of the reproducing machine without affecting the purity of tone and without causing those harsh and blasting sounds which are sometimes produced to be magnified by the amplifier, and which at the same time will 20 resonate in accord with the musical sounds being reproduced in a manner to enhance the quality of the tone.

A further object of the invention is to 25 provide an amplifier having the above qualifications which is capable of being embodied in the form of a so-called concealed horn or amplifier for use in existing types of reproducing machines without change in the 30 structure of other parts of the machine.

Various other objects of my invention will be apparent from a perusal of the following specification and the drawings accompanying the same.

35 My invention is illustrated in the accompanying drawings in which—

Figure 1 is a front elevation.

Fig. 2 is a top plan view.

Fig. 3 is a side elevation with the near 40 side of the horn removed to show the interior parts.

Referring to the drawings in detail, it will be seen that the horn consists of the top and side walls 1, 2, 3 and 4 which taper and 45 approach each other toward the back to form a rectangular funnel having the front portion braced by the frame 5, the rear portion connecting in any suitable manner with the usual elbow or throat leading to the 50 tone arm not shown.

Intermediate the length of the horn and bearing against the upper and lower walls 1 and 2 is a brace 6 and a short distance in front of this brace I provide a tightening 55 rod 7 arranged to be tensioned by means of

a suitable turn buckle 8 connected intermediate its ends, the ends of the rod passing through the upper and lower walls and terminating in headed portions 9 and 10 which bear inwardly on the walls through bridges 60 11 and 12 respectively. The feet of the bridges 11 and 12 and the feet 13 of the central brace 8 bear on the upper and lower walls of the amplifier through pads 14 and 15 respectively, of felt or other suitable material. By tightening the rod 17 the top and bottom walls are put under tension by the inward pressure of the bridges 11 and 12 and the outward pressure of the middle and front braces 6 and 5 and the side walls 3 70 and 4. Each of the side walls 3 and 4 is arranged to be put under lateral tension by means of tightening rods 16 and 17 which bear inwardly on the central portion of the side walls 3 and 4 through bridges 18 and 19 75 and outwardly on the upper and lower edges of the side walls through the inner bridges 20 and 21. The tightening rods 16 and 17 bear against their respective outer bridges through heads 22 and against their inner 80 bridges through the wing nuts 23 which serve as means for varying the pull or tension on their respective rods 16 and 17.

Suitable pads 24 are placed between the side bridges 18 and 19 and the side walls. 85 It will be seen that by tightening the wing nuts 23 the side walls are tensioned inwardly at the center and are made to bear against the inside bridges 20 and 21 and the sides of the front brace 5. Thus with the 90 structure above described, all four sides of the amplifier may be put under tension and the tension adjusted to cause the horn to so resonate in accordance with the sounds being reproduced as to produce the most desirable quality of tone. As the different parts of the amplifier are all tensioned inwardly and against each other and the various braces, there is no lost motion or loose play between them. Also the sides being 95 tensioned are given a surface or skin tension which makes for increased resiliency.

It is to be noted that while I have herein described and shown one specific embodiment of my invention, for the purpose of 100 disclosure, it is to be understood that I do not limit myself to such specific embodiment but contemplate all such reversals, variants and modifications as fairly fall within the scope of the appended claims. 110

Having thus described my invention what I claim and desire to secure by Letters Patent is:

1. A sound amplifier for talking machines comprising top, bottom and side walls inclosing a tapering chamber, with non-resonant bridge tensioning means applied to said walls, each bridge having end supports engaging a wall to exert a thrust thereon at separated points thereof, and intermediate means to draw the same wall against the said end supports, all of said engaging parts

being insulated as to sound vibration from the said walls.

2. A sound amplifier as claimed in claim 1 having intermediate tensioning means composed of rods engaging supplemental bridges engaging the walls of the amplifier on opposite sides from the main bridges and similarly insulated therefrom as to sound. 20

In testimony whereof I affix my signature.

JOSEPH MERSMAN.
